UNITED STATES PATENT OFFICE.

ISAAC A. FRASER, OF PROVIDENCE, RHODE ISLAND.

STEAM-BLOWER.

SPECIFICATION forming part of Letters Patent No. 749,050, dated January 5, 1904.

Application filed August 29, 1903. Serial No. 171,205. (No model.)

To all whom it may concern:

Be it known that I, ISAAC A. FRASER, a resident of the city of Providence, in the county of Providence and State of Rhode Island, have 5 invented certain new and useful Improvements in Steam-Blowers; and I do hereby declare that the following is a full, clear, and exact description thereof, reference being had to the accompanying drawings, and to the letters of reference marked thereon, which form a part of this specification.

My invention relates to steam-blowers for producing forced draft in boilers, and has for its object the production of a blower whereby 15 steam is forced in jets from a plurality of hollow rings to draw a large body of air from the outside of a furnace or boiler through a tube or funnel and force the same in great volume up amid the mass of fuel upon the grate of 20 the furnace to facilitate the combustion of the same.

My invention is fully described in this specification and illustrated in the accompanying drawings, in which—

25 Figure 1 is a longitudinal section of the tube or shell and steam-rings within it, said section being taken approximately on line 1 1 of Fig. 2, which latter figure shows the rings removed. Fig. 2 is a front view of the two 30 steam-rings removed from the tube. Fig. 3 is a plan view showing the recess in the bell-shaped mouth of said tube, said recess being for the reception of the bosses on the steam-ring for the pipe connections. Fig. 4 is a longitudinal section of the bell-shaped mouth of 35 the tube, taken on line 4 4 of Fig. 3.

Referring to the drawings, A is the tube or shell, constructed, preferably, of metal and is made slightly tapering, being somewhat 40 smaller at its inner end and rounding out into a bell shape at its outer end or mouth. Into the flaring bell-shaped mouth of this shell A is set a large hollow ring C. This ring is in the circular form shown, the exterior wall 45 thereof being substantially flat and conforming to the contour of the bell-mouth of shell A, the inner wall being convexed and provided with a forward face arranged on a bevel or at a slight angle and is provided with a series of apertures D, through which the steam 50 is forced. On the top and bottom of this ring C are the bosses C' C', which bosses fit into

corresponding recesses B B, made for their reception in the walls of the mouth of the shell. These bosses C' C' are to receive the 55 threaded steam-pipe and exhaust or drip pipes C² C³. The ring may thus be held in position without coming in contact with the shell, if desired. In the center of this large steam-ring C is a smaller hollow steam-ring 60 E, circular in form and, like the larger ring, has a series of small apertures F, through which the steam is forced. This ring E is suspended and supported from the large ring C by means of the steam-pipes e e'. In the 65 pipe e' is the union e², which is for the purpose of facilitating the connection of the middle ring.

The operation of my device is further explained as follows: The tube or shell A may 70 be attached to the ash-pit door or set in the brick wall of the boiler and held in place by suitable brackets G G, bolted to the shell, as illustrated in Fig. 1. The steam-pipe C² may be led from the boiler to the rings in any 75 suitable manner and suitable shut-off valves employed to control the flow of the same.

The essential feature of my invention is the use of a tapering shell or tube having a bell-shaped mouth, into which mouth is placed 80 two or more steam-rings, one located within the other, the holes in both of the rings being so located that the steam emitted therefrom spreads just enough to completely fill the small end of the shell, as illustrated in 85 Fig. 1.

It is found in practice that by the use of this center ring in connection with the outside ring a perfect distribution of steam is obtained, completely filling the tube. The 90 steam thus injected moves rapidly inward, carrying with it a large quantity of air, forcing the same with great velocity by the use of but a small quantity of steam up through the tightly-packed fuel on the grate, materially increasing the combustion of the same, 95 and consequently the efficiency of the boilers.

By so effectively distributing the jets about the mouth of the tube through which the steam is emitted a minimum quantity of 100 steam may be used to produce the maximum amount of work.

In the construction above described I obtain a very powerful draft with but little ex-

penditure of power, and by using but little steam I reduce the cost of operating and also perceptibly reduce the noise which usually attends the operation of these machines and which heretofore has been a very objectionable feature.

The device is extremely efficient, as well as very simple and practical in construction.

Having thus described my invention, what

10 I claim as new, and desire to secure by Letters Patent, is—

15 1. A steam-blower comprising a tube, and a steam-ring supported in the mouth thereof, the exterior wall of said ring conforming to the contour of said mouth, said ring being provided with a plurality of outlet-orifices.

20 2. A steam-blower comprising a tube, a steam-ring supported in the mouth thereof, the exterior wall of said ring conforming to the contour of said mouth, an inner ring concentric to said former ring, said rings being each provided with a plurality of outlet-orifices.

25 3. A steam-blower comprising a tube having a bell-mouth, and a steam-ring supported within and conforming to the contour of said mouth, said ring being provided with a plurality of outlet-orifices.

30 4. A steam-blower comprising a tube having a bell-mouth, and a steam-ring supported in said mouth, said ring having an outer wall

conforming to the contour of said bell-mouth, the inner wall of said ring being convex in cross-section, said ring being also provided with a plurality of outlet-orifices.

35

5. A steam-blower comprising a tube, and a steam-ring supported within and conforming to the contour of the mouth thereof, said ring having a forward beveled face provided with a plurality of outlet-orifices.

40

6. A steam-blower comprising a tube having a bell-mouth, a steam-ring supported in said mouth, said ring having an outer wall conforming to the contour of said bell-mouth, the inner wall of said ring being convexed in cross-section, and an inner ring concentric to said former ring, said rings being each provided with a plurality of outlet-orifices.

45

7. In a steam-blower, a tube having a bell-mouth, recesses being formed in the walls of said mouth, a steam-ring mounted within said mouth and conforming to the contour thereof, and bosses formed on said ring and fitting within said recesses, said ring having a plurality of outlet-orifices.

50

In testimony whereof I have hereunto set my hand this 28th day of August, A. D. 1903.

ISAAC A. FRASER.

In presence of—

HOWARD E. BARLOW,
FRANK A. FOSTER.
